UNITED STATES PATENT OFFICE.

JUAN JULIAN GURIDI, OF MANSAVILLAGRA, FLORIDA, URUGUAY.

HARROW AND LOCUST-KILLING MACHINE.

1,306,059.

Specification of Letters Patent. Patented June 10, 1919.

Application filed August 3, 1918. Serial No. 248,170.

To all whom it may concern:

Be it known that I, JUAN JULIAN GURIDI, citizen of Uruguay, residing at Mansavillagra, Florida, Uruguay, have invented certain new and useful Improvements in Harrows and Locust-Killing Machines, of which the following is a specification.

The present invention relates to a new harrow and locust killing machine which by its novel construction, easy working, low cost and its use, either as a harrow or as a locust killing machine, as well as by the results which it gives in both cases,—as will be hereinafter described,—makes it a valuable acquisition for persons engaged in agriculture. I shall herein describe the invention primarily as a locust killing apparatus, in which embodiment it is exceedingly simple in operation.

20 The capacity of the machine according to the type used is of 4 to 26 hectares per day. The various types differ only in size and in the number of cutting and crushing disks, without altering in any way the constructive 25 form, etc.

The present invention presents a great advantage over fire locust killing apparatus if the fact is taken into consideration, that the latter only have a maximum radius of 30 action of about 8 inches, and their employment is dangerous because they are always subject to explosion and also expensive on account of the continuous use of fuel, and, furthermore, it is necessary, in order to 35 avoid accidents, that they should be run by adults to whom higher wages have to be paid; whereas, my machine, taking the smallest size, covers a killing area of about 72 inches, does not require the expense of 40 fuel and a child can handle it.

It may be argued, that the cost of my machine is higher than that of the fire killing apparatus, but it must be borne in mind, that my machine is a locust killing machine 45 and a harrow at the same time; that as soon as the work of killing is done it can be used as a harrow with great advantage in farming work, and even when a fire locust killing machine is of lower cost initially it will 50 be more expensive in the end, on account of the consumption of fuel, which in only ten days of continuous work will exceed the difference of the initial cost between the two machines.

55 Compared with the so-called incinerating machines which are intended to exterminate

the locust and afterward to be used in an industrial manner, my machine certainly presents advantages because, with the other machine it is necessary to allow the locust 60 to live until it is able to fly, so that the machine may do its work. Furthermore, the incinerating machine is of a prohibitory price for the farmer, of moderate means, who really is the one who suffers most from 65 locusts. My machine is also more advantageous for while the incinerating machine clears a hectare mine clears three or four hectares.

In regard to the use of the invention as 70 a harrow, it gives excellent results and is superior to all types of harrows heretofore known, because it can be used at any time and specially in dry weather, whereas, the 75 the others cannot work at all times. After the harrow goes over the soil, the plow will make a better furrow and break the ground very fine. Furthermore, harrows provided with single axle are inferior to the present invention which is provided with four axles, 80 because when working on the ground already broken the surface of which is uneven, as all the disks are on the same axle, when a disk passes over an elevation or rock, it 85 will raise all the other disks so that the harrow loses all effect upon the ground adjacent to the elevation or rock, whereas, with my harrow, even if the disks of one axle lose 90 their action on account of an obstruction, the other disks which are on the other axles 95 will complete the work.

The change of my machine from locust killer to harrow and vice-versa is very simple. It is sufficient to withdraw or put on 95 the tires of the crushing disks which are attached thereto by means of bolts in order to make the necessary change.

In order to clearly explain the method of construction and manner of using my machine, the same will now be described with 100 reference to the accompanying drawings, in which,

Figure 1 is a plan view of the machine;

Fig. 2 is a side view of same;

Fig. 3 is a view of one of the crushing 105 disks;

Fig. 4 is a section of said disk showing one method of setting and

Fig. 5 is an end view of the brush employed to sweep the locusts toward the 110 machine.

In Fig. 1 A are the crushing disks. B are

the disks to fill the clear spaces which together with the disks A after the removal of the crushing tires make the harrow. The disks B are also used as a barrier to carry 5 the locusts under the crushers. C is an adjustable brush which is used for sweeping the locusts toward the crushers and also increases the radius of action of the machine. D are the axles and bearings of the crushing 10 disks. E are the axles and bearings of the plain disks. F are the parts which form the frame of the machine. G are the reinforcing braces of the frame. H is the shaft or pole for drawing. I is a draft equalizer bar. 15 J is an arm of the brush C. K are the removable crushing tires of the disks A. L is the cable for adjusting the positions of the brush C. M is the side brush attached to pole H which acts as a barrier and N are 20 supports located at the upper part of the apparatus.

In Figs. 2 and 3, A shows the disks and K the bipart crushing tires which are attached to the disks by means of bolts.

25 In Fig. 4, P are the dowel pins to connect the abutting sectional faces of the bipart crushing tires.

In Fig. 5, J is a section of the arm of the brush support O and C is a section of the 30 brush.

In order to run my machine all that is necessary is to harness the draft animal to the pole H. When working as locust killer the brush C will be given (by means of the 35 opening and closing cable L) the angle that should be necessary to cover more or less ground and carry the locusts under the machine. When working as a harrow the brush should be raised because its use is not necessary. 40

The invention might be rendered more efficient for ground of irregular surface by placing the axles of the plain and crushing disks on resilient bearings, so that these 45 might go up or down adapting themselves to all the roughness of the ground where the locusts are to be destroyed; but with a view to cheapening the cost of the machine as much as possible, I have thought more suit-

able to adopt the type of fixed axle, but the 50 use of this preferred embodiment should not be taken to preclude my right to the alternative arrangement. The fixity of the axles is not, however, an obstacle for the greater 55 output of the machine, because the same result can be obtained, as it is very easy to drive a swarm of locusts when they are only in condition to jump, to flat ground where the machine could work with complete facility. 60

In regard to the brush C this may be made in a revolving cylindrical form for which it will be necessary to put the corresponding gear to actuate the same but up to now I have thought it more suitable, in order to 65 cheapen the cost of the machine, to make it in a fixed form, without however renouncing my rights to use the rotary cylindrical brush, if it should be deemed suitable.

What I claim is:

1. A combined harrow and locust-killing machine comprising a supporting frame, a series of axles thereon, and a number of disks rotatable on said axles, said disks being alternately provided with detachable tires, a 75 single tire being provided for one disk only, whereby the machine may be used either as a harrow or as a locust-killing machine.

2. Apparatus of the kind described, comprising a supporting frame, a series of axles 80 thereon, a number of disks rotatable on said axles, the disks on one axle being simple cutting disks while the disks on the other axle are crushing disks, a brush and controlling means for said brush.

3. Apparatus of the kind described, comprising a supporting frame, a series of axles thereon, a number of alternately placed cutting disks and crushing disks rotatable on 85 said axles, said crushing disks comprising two coöperative members adapted to be bolted to the disks, a brush, controlling means for said brush, and a barrier brush.

In testimony whereof I affix my signature
JUAN JULIAN GURIDI
